(57) **CLAIM**

I claim the ornamental design for a plant growing container, as shown.

DESCRIPTION

FIG. 1 is a right, front, top perspective view of the plant growing container showing my new design;

FIG. 2 is a front elevation view thereof;

FIG. 3 is a rear elevation view thereof;

FIG. 4 is a left side plan view thereof;

FIG. 5 is a right side plan view thereof;

FIG. 6 is a top elevation view thereof; and,

FIG. 7 is a bottom elevation view thereof.

The shade lines in the Figures show contour and not surface ornamentation.

1 Claim, 7 Drawing Sheets
